UNITED STATES PATENT OFFICE.

HENRY H. CLOUGH, OF ELYRIA, OHIO.

RAILWAY-TIE PLATE AND MEANS FOR SECURING A RAIL THERETO.

SPECIFICATION forming part of Letters Patent No. 793,054, dated June 27, 1905.

Application filed March 14, 1904. Serial No. 197,966.

To all whom it may concern:

Be it known that I, HENRY H. CLOUGH, a citizen of the United States, and a resident of Elyria, Lorain county, Ohio, have invented 5 certain new and useful Improvements in Railway-Tie Plates and Means for Securing a Rail Thereto, of which the following is a complete specification.

This invention relates to tie-plates, and relates particularly to tie-plates of the general type which forms the subject-matter of an application for Letters Patent of the United States, filed by me in the Patent Office concurrently herewith, Serial No. 197,965.

15 The object of the present invention is to provide a modified form of means for securing the rails to the tie-plates from the means shown, described, and specifically claimed in said application above identified.

20 The present invention consists of the various features, combinations of features, and details of construction hereinafter described and claimed.

In the accompanying drawings a tie-plate 25 and securing means embodying the invention of the present application are fully illustrated.

Figure 1 is a top plan view of a tie-plate, showing a rail secured thereto by means embodying my present invention. Fig. 2 is a 30 sectional view thereof on the line 2 2 of Fig. 1. Fig. 3 is an enlarged perspective view of a clamping-dog forming part of the securing means. Fig. 4 is an enlarged sectional view on the line 4 4 of Fig. 1. Figs. 5, 6, and 7 35 are views similar to Figs. 1, 2, and 3, respectively, illustrating a modification of the securing means shown in said Figs. 1, 2, and 3. Figs. 8 and 9 are views similar to Figs. 5 and 6, illustrating a modified form of means 40 for securing the clamping-dogs in adjusted position. Fig. 10 is an enlarged sectional view on the line 10 10 of Fig. 8, and Figs. 11 and 12 are enlarged detail views.

Referring now to the drawings, 1 designates a tie-plate to which the rail 2 is adapted to be secured in the following manner: Formed in the tie-plate 1 are slots 3, which are disposed outside of and extend obliquely relatively to the rail-seat on said tie-plate.

Secured in the slots 3 by means of suitable 50 heads 4 thereon, so as to be movable lengthwise of said slots, are dogs 5, the inner ends of which are adapted to extend over the bases of the rails, the relation being such that as said dogs 5 are forced or driven lengthwise 55 of the slots 3 toward the rail 2 the ends thereof, which extend over the rail-bases, will be drawn into strong engagement therewith, thereby clamping the base of said rail firmly to the tie-plate and operating to secure said 60 rail firmly in position upon its seat.

In the preferable construction (shown in Figs. 1 to 4, inclusive, of the drawings) the slots 3 are T-slots, and the inner ends of the dogs 5, which engage the bases of the rails, 65 extend at an angle relatively to the corresponding sides of the heads 4, the relation being such that at the sides of said dogs designed to be inserted into said T-slots 3 first the surfaces on said dogs which engage the rail-bases 70 will be directly opposed to the shoulders on the heads 4, which engage the inner flanges of the T-slots 3, as shown at 6, Fig. 3, the relation being such that as the dogs are driven or forced into engagement with the bases of 75 the rails the opposed surfaces or shoulders 6 will exert a gripping or clip action, tending to draw the rails and tie-plates together, the force of which will be additional to the ordinary lever action exerted by said dogs. As shown 80 in Figs. 5 to 12, inclusive, the slots 3 and dog-heads 4 are made in the form of dovetails. As shown, the dogs 5 are cut away or recessed at the points where they engage the bases of the rails, said recesses conforming substantially to the shape of said rail-bases where they are engaged by said dogs, as shown at 7. This, however, is not essential, as the form of 85 said dogs may be varied without departure from my invention. Due to the fact that the 90 slots 3 extend obliquely to the rail-seats it is obvious that the same tie-plates may be used with rails having bases of different widths. After the dogs 5 have been forced or driven 95 into desired engagement with the bases of the rails they are adapted to be secured in adjusted position by suitable means.

As shown in Figs. 1 to 7, inclusive, said

dogs are adapted to be secured in adjusted position by means of set-screws 8, threaded through said dogs and adapted to bear upon rigid portions of the tie-plates 1, as shown 5 the bottoms of the slots or grooves 3. In what I now consider the preferable construction, however, said dogs 5 are adapted to be secured in adjusted position in the following manner: Formed on the bottoms of the slots or grooves 10 10 3 are teeth 9, the sides or faces of which away from the outer ends of said slots are preferably vertical, or substantially so, and the opposite faces of which toward the outer ends of said slots are preferably upwardly and rearwardly inclined. Fitted to suitable bearings in the dogs 5, so as to be freely movable toward and from the teeth 9, are blocks 10, formed on the lower surfaces of which are teeth 11, the shape of which corresponds to 15 the shape of the teeth 9 on the tie-plate, the front faces thereof being substantially vertical and the rear or inner faces upwardly and rearwardly inclined. To prevent turning of the blocks 10, which would bring the rack-teeth 11 thereon out of alinement with the teeth 9, suitable means are provided to prevent turning of said blocks in their bearings. As shown, this is effected by making said 20 blocks square or rectangular in cross-section. 25 30 To provide for disengaging the teeth 11 on the blocks 10 from the teeth 9 on the tie-plate, means are provided as follows: Formed on the blocks 10 are shanks 12, which are fitted to and extend upwardly through suitable 35 openings formed in the dogs 5 and are of such length that they will project above the tops of said dogs. The upper ends of the shanks 12 on said blocks 10 are screw-threaded, and adjusted thereto are nuts 13. With 40 this construction it is obvious that turning the nuts 13 when they bear against the tops of the dogs 5 will operate to raise the blocks 10 and to withdraw the teeth 11 thereon from engagement with the teeth 9, thus making 45 provision for releasing the dogs 5 when desired. It is also obvious that the blocks 10 will be supported in raised position until the nuts 13 are again unscrewed. When inserting the dogs 5 into the slots or grooves 3, the 50 blocks 10 will preferably be secured in raised position, so as to be entirely clear of the teeth 9. It is obvious, however, that even should said blocks be in lowered position the inclination of the faces thereof will operate 55 to raise them as said dogs are forced or driven inwardly, so that said blocks will not interfere with the inward movement of said dogs. After the dogs 5 have been forced or driven into desired engagement with the bases of 60 the rails the nuts 13 will be unscrewed, allowing the blocks 10 to fall, thereby bringing the teeth 11 thereon into engagement with the teeth 9 on the tie-plate, which will oper-

ate in an obvious manner to prevent movement of the dogs 5 in a direction to release 65 the rail until said blocks are again raised in the manner heretofore described.

While I have herein shown two clamping devices on each tie-plate disposed on opposite sides of the rail-seat, it is obvious that each 70 tie-plate may be provided with but a single set of securing devices, successive plates comprising securing devices disposed on opposite sides of the rail-seats thereon.

Any desired or approved means may be 75 used for securing the tie-plates 1 to the ties. As shown, the tie-plate 1 comprises a web or flange 14, adapted to be secured to the metal core of a concrete tie in the manner fully shown, described, and claimed in an application for United States Letters Patent, filed by me in the Patent Office concurrently herewith, Serial No. 197,964, to which reference is made for a detailed description thereof.

I claim as my invention— 85

1. The combination with a tie-plate, of means for securing a rail thereto, said means comprising a slot in said plate which extends obliquely to the rail-seat, a clamping-dog and a head thereon secured in said slot, substantially as described. 90

2. The combination with a tie-plate, of means for securing a rail thereto, said means comprising a slot in said plate which extends obliquely to the rail-seat, a clamping-dog and 95 a head thereon secured in said slot, the inner end of said dog being designed and adapted to engage the base of a rail and the outer end thereof resting in contact with the surface of said tie-plate at the side of said slot remote from the rail-seat, substantially as described. 100

3. The combination with a tie-plate, of means for securing a rail thereto, said means comprising a T-slot formed in said tie-plate which extends obliquely to the rail-seat, a 105 clamping-dog and a head thereon which is secured in said T-slot, the relation being such that at the side of said dog designed to be inserted into said T-slot first, the end of said dog which engages the rail-base will be opposed to the shoulder on the head of the dog which engages the inner flange of said T-slot, substantially as described. 110

4. The combination with a tie-plate, of means for securing a rail thereto, said means comprising a T-slot which extends obliquely to the rail-seat, a clamping-dog, and a head thereon which is secured in said T-slot, the end of said clamping-dog which engages the rail-base extending at an angle relatively to the corresponding side of the head on said clamping-dog in such manner that at the side of said dog designed to be inserted into said T-slot first, the surface of said clamping-dog which engages the rail-base will be directly 120 opposed to the shoulder on the head of the dog 125

which engages the inner flange of said T-slot, substantially as described.

5. The combination with a tie-plate, of means for securing a rail thereto, said means comprising a T-slot formed in said tie-plate which extends obliquely to the rail-seat, a clamping-dog and a head thereon which is secured in said T-slot, the relation being such that at the side of said dog designed to be inserted into said T-slot first, the end of said dog which engages the rail-base will be opposed to the shoulder on the head of the dog which engages the inner flange of said T-slot, and an extension on said clamping-dog which 15 engages said tie-plate at the side of the T-slot therein remote from the rail-seat, substantially as described.

6. The combination with a tie-plate, of means for securing a rail thereto, said means being adjustable relatively to said tie-plate, and means for securing the same in adjusted position, substantially as described.

7. The combination with a tie-plate, of means for securing a rail thereto, said means comprising a clamping member which is adjustable relatively to said tie-plate, and means to secure said clamping member in adjusted position, substantially as described.

8. The combination with a tie-plate, of means for securing a rail thereto, said means comprising a clamping member which is adjustable relatively to said tie-plate, and means to secure said clamping member in adjusted position, said means comprising teeth formed 35 on said tie-plate, a block fitted to a suitable bearing in said clamping member so as to be movable toward and from the teeth on said tie-plate, and teeth on said block adapted to engage the teeth on said tie-plate, substantially 40 as described.

9. The combination with a tie-plate, of means for securing a rail thereto, said means comprising a clamping member which is adjustable relative to said tie-plate, and means 45 to secure said clamping member in adjusted position, said means comprising teeth formed on said tie-plate, a block fitted to a suitable bearing in said clamping member, so as to be movable toward and from the teeth on said tie-plate, teeth on said block adapted to engage the teeth on said tie-plate, and means to 50 retract said block to disengage the teeth thereon from the teeth on said tie-plate, substantially as described.

55. 10. The combination with a tie-plate, of means for securing a rail thereto, said means comprising a clamping member which is adjustable relatively to said tie-plate, and means to secure said clamping member in adjusted 60 position, said means comprising teeth formed on said tie-plate, a block fitted to a suitable bearing in said clamping member so as to be movable toward and from the teeth in said

tie-plate, teeth on said block adapted to engage the teeth on said tie-plate, a shank on 65 said block which extends upwardly through a hole or opening formed in said clamping member, and a nut threaded to the projecting end thereof, substantially as described.

11. The combination with a tie-plate, of 70 means for securing a rail thereto, said means comprising a clamping member which is adjustable relatively to said tie-plate, and means to secure said clamping member in adjusted position, said means comprising teeth formed 75 on said tie-plate, a block fitted to a suitable bearing in said clamping member so as to be movable toward and from the rack-teeth on said tie-plate, teeth on said block adapted to engage the teeth on said tie-plate, means to 80 prevent turning of said block, and means to retract said block to disengage the teeth thereon from the teeth on said tie-plate, substantially as described.

12. The combination with a tie-plate, of 85 means for securing a rail thereto, said means comprising a clamping member which is adjustable relatively to said tie-plate, and means to secure said clamping member in adjusted position, said means comprising teeth formed 90 on said tie-plate, a rectangular block fitted to a suitable bearing in said clamping member so as to be movable toward and from the teeth on said tie-plate, teeth on said block designed and adapted to engage the teeth on said tie-plate, a shank on 95 said block which extends upwardly through a hole in said clamping member, and a nut threaded to the projecting end thereof, substantially as described.

13. The combination with a tie-plate, of 100 means for securing a rail thereto, said means comprising a slot formed in said tie-plate which extends obliquely to the rail-seat, a clamping-dog, a head thereon which is secured in said slot, and means comprising teeth formed 105 on the bottom of said slot, a rectangular block fitted to a suitable bearing in said dog so as to be movable toward and from the teeth on the bottom of said slot, teeth on said block adapted to engage the teeth on the bottom of 110 said slot, a shank on said block which extends upwardly through a hole in said dog and a nut threaded to the projecting end thereof, substantially as described.

14. The combination with a tie-plate, of 115 means for securing a rail thereto, said means comprising a clamping member which is adjustable relatively to said tie-plate, and means to secure said clamping member in adjusted position, said means comprising teeth on said 120 tie-plate, a block fitted to a suitable bearing in said clamping member so as to be movable toward and from the teeth on said tie-plate, teeth on said block designed and adapted to engage the teeth on said tie-plate, the front 125 sides or faces of the teeth on said plate and

the rear sides of the teeth on said block being correspondingly rearwardly inclined and the rear sides or faces of the teeth on said tie-plate and the front sides or faces of the teeth on said block being substantially vertical, and means to retract said block to disengage the teeth thereon from the teeth on said tie-plate, substantially as described.

In testimony that I claim the foregoing as my invention I affix my signature, in presence ¹⁰ of two subscribing witnesses, this 10th day of February, A. D. 1904.

H. H. CLOUGH.
